ROTARY MOWER HOUSING

James F. Gadbois, Minneapolis, Minn., assignor to Toro
Manufacturing Corporation, Minneapolis, Minn., a cor-
poration of Minnesota

Filed Oct. 16, 1958, Ser. No. 53,004

Term of patent 14 years

(Cl. D40—1)

FIG. 1

FIG. 2

FIG. 3

FIG. 4

Fig. 1 is a top perspective view of a rotary mower housing embodying my new design as viewed from the front;

Fig. 2 is a top perspective view of the same as viewed from the rear;

Fig. 3 is a bottom perspective view of the same; and
Fig. 4 is a side elevational view of the same.

I claim:

The ornamental design for a rotary mower housing, as shown.
